UNITED STATES PATENT OFFICE.

MAX BUCHSBAUM, OF NEW YORK, N. Y.

SKIRT-MARKER.

985,508.

Specification of Letters Patent. Patented Feb. 28, 1911.

Application filed July 14, 1909. Serial No. 507,482.

To all whom it may concern:

Be it known that I, MAX BUCHSBAUM, a citizen of the United States of America, residing at New York city, in the county of 5 New York and State of New York, have invented certain new and useful Improvements in Skirt-Markers, of which the following is a specification, reference being had therein to the accompanying drawing.

10 This invention relates to devices for gag-
ing and marking the length of skirts, gar-
ments, cloaks, or other apparel for women
and children, and it is especially adapted for
use of cutters and fitters in tailoring estab-
lishments. Heretofore devices of this kind
have been troublesome to use because of the
difficulty of drawing the chalk, or other
marking material, across the goods or the
goods across the chalk while the garment
20 is hanging on the person being measured.
The drawing of the chalk across the goods
had a tendency to shift them out of posi-
tion, and thereby make the measurements
less exact and more unreliable.
25 The object of my invention is to provide a
device which will print or stamp the mea-
surements desired on the goods, in contra-
distinction to one in which it is necessary
30 to draw a line across them, and further to
provide an apparatus which will be more
cheap, simple, absolutely reliable and ac-
curate, and easier to operate than those
formerly used.

To this end my invention consists in the
35 peculiar features and combinations of parts
more fully described hereinafter and point-
ed out in the claims.

In the accompanying drawings, Figure 1
represents a perspective view of my com-
40 plete invention, wherein dotted lines indi-
cate the garment of a woman in the act of
being measured. Fig. 2, a plan view of the
main portion of my device. Fig. 3, a top
45 perspective detail view of a marking slide,
and Figs. 4, 5 and 6, views of details.

The wearer of a garment 1, shown in dot-
ted lines, stands upon a foot stool 2, in the
manner customary to those who are having
garments measured and marked by a cutter
50 or tailor. 3 is a base rising perpendicu-
larly from the front of this base and sec-
ured thereto is a convex or curved shell 4
constituting a platen, preferably made of
some light sheet metal so that the two parts
55 form a substantially L-shaped structure.
The curvature of the shell corresponds sub-

stantially to the curvature of the foot stool
2, or of the garment to be measured. The
upper edge 13 of this shell 4 is curved trans-
versely, so that the dress may fall over the 60
shell with facility preparatory to marking
it. The marking operation is accomplished
by means of a sliding horizontal marker or
impression type 5 adapted to slide up and
down on a vertical fork 6 placed opposite 65
the shell 4. The right hand edge of the
sliding marker is provided with a curved
edge 7 corresponding with the curvature of
the shell 4. This edge is roughened for the
purpose of receiving an application of chalk, 70
so that when it is pressed against the gar-
ment and the garment against the shell a
line will be marked on the garment to indi-
cate the proper length desired.

As seen in Fig. 5, the vertical fork 6 is 75
provided with a scale 8, which indicates the
exact height of the marker, and the fork is
secured to and carried by a horizontal run-
ner or slide 9 which works back and forth
between the pair of guides 10 on the base 3, 80
the fork and slide together also forming a
movable L-shaped member. The handle 11
enables the operator to move the slide 9, and
hence the marker, toward and from the
platen 4. The marker 5 may be moved and 85
locked in any desired elevation upon the
fork 6 by means of a clamping screw 12.
The element which is called a shell, over
which the garment is adapted to hang,
should with propriety be called a platen, be- 90
cause it serves as such when it receives the
force of the marker 5 which advances in a
right line and acts like a type upon it in the
act of printing with chalk the desired
height. By moving the instrument around 95
the stool and hence the garment, a true circle
can be printed or stamped upon the latter
at a uniform distance from the floor with
unfailing accuracy, because the garment does
not yield when pressed upon by the marker, 100
and because the latter is held always at a
uniform distance from the floor. If it is
not convenient to move the marker around
the garment, the person being measured can
turn completely around instead and the de- 105
sired marking be performed.

Although I have shown a specific con-
struction for carrying out my invention, it
is obvious that innumerable changes might
be made therein without departing from the 110
spirit and scope of my device, and therefore
I wish it understood that I do not limit

myself to the precise construction herein shown and described, but consider myself entitled to all such changes as may be made within the spirit and scope of my invention.

5 Having thus described my invention, what I claim as new and desire to secure by Letters Patent is:

1. In a skirt or garment marker, the combination with an upright platen over which 10 a garment or skirt is adapted to fall, of a horizontal base to which it is rigidly secured said base having guiding means, a horizontal runner or slide adapted to work back and forth in said guiding means, an 15 upright fork carried by said runner and movable toward and away from the platen, a manually movable printing marker adapted to slide up and down upon said fork, and means for locking said marker in any desired position to which it may be adjusted.

2. In a skirt or garment marker, the combination of an upright platen over which the garment or skirt is adapted to fall, a supporting horizontal base to which the platen is fixedly secured, an upright fork arranged 25 to move toward and away from the platen, said fork having also a base, a printing device provided with a face adapted to receive and carry the marking pigment, said device being adapted to slide up and down upon 30 the upright fork, and means for holding the printing device in any desired position to which it may be adjusted.

In testimony whereof I affix my signature in presence of two witnesses.

MAX BUCHSBAUM.
